(57) **CLAIM**

The ornamental design for a main unit of a handheld vacuum cleaner as shown and described.

DESCRIPTION

1.1 is a front view of a first main unit of a handheld vacuum cleaner;

1.2 is a back view thereof;

1.3 is a left view thereof;

1.4 is a right view thereof;

1.5 is a top view thereof;

1.6 is a bottom view thereof;

1.7 is a front, left, top perspective view thereof;

1.8 is a rear, right, top perspective view thereof;

1.9 is a rear, right, bottom perspective view thereof.

2.1 is a front view of a second main unit of handheld vacuum cleaner;

2.2 is a back view thereof;

2.3 is a left view thereof;

2.4 is a right view thereof;

2.5 is a top view thereof;

2.6 is a bottom view thereof;

2.7 is a front, left, top perspective view thereof;

2.8 is a rear, right, top perspective view thereof; and

(Continued)

2.9 is a rear, right, bottom perspective view thereof.
